UNITED STATES PATENT OFFICE

127,377

DESIGN FOR AN ATTACHING MEMBER FASTENER

Conrad Nilsen, Mattapan, Mass.

Application January 30, 1941, Serial No. 93,517

Term of patent 7 years

To all whom it may concern:

Be it known that I, Conrad Nilsen, a citizen of the United States and a resident of Mattapan, in the county of Suffolk and State of Massachusetts, have invented a new, original, and ornamental Design for an Attaching Member Fastener, of which the following is a specification, reference being had to the accompanying drawing, forming a part thereof, in which

Fig. 1 is a top plan view of the attaching member fastener showing my new design;

Fig. 2 is a side elevation of the attaching member fastener;

Fig. 3 is a sectional view taken along the line 3—3 of Fig. 1; and

Fig. 4 is a sectional view taken along the line 4—4 of Fig. 1.

I claim:

The ornamental design for an attaching member fastener, as shown.

CONRAD NILSEN.
